[57] CLAIM

The ornamental design for electronic balance, as shown.

DESCRIPTION

FIG. 1 is a top plan view of an electronic balance showing my new design;

FIG. 2 is a front elevational view;

FIG. 3 is a bottom plan view;

FIG. 4 is a right side elevational view;

FIG. 5 is a left side elevational view;

FIG. 6 is a rear elevational view;

FIG. 7 is a top, front, and left side perspective view;

FIG. 8 is a top, front, and left side perspective view, the display screen showing typical indica; and,

FIG. 9 is a top, front, and left side perspective view of another embodiment of my new design of FIGS. 1-8.

FIG. 1

FIG. 2

FIG. 4

FIG. 3

FIG. 5

FIG. 6

FIG. 7

FIG. 8

FIG. 9
